UNITED STATES PATENT OFFICE.

JAMES MILTON WADSWORTH AND ELMER GEORGE BRUA, OF OAKLAND, CALIFORNIA.

MAP-FILING CABINET.

1,050,409.

Specification of Letters Patent. Patented Jan. 14, 1913.

Application filed February 23, 1911. Serial No. 611,541.

To all whom it may concern:

Be it known that we, JAMES MILTON WADSWORTH and ELMER GEORGE BRUA, citizens of the United States, residing at Oakland, in the county of Alameda and State of California, have invented a new and useful Map-Filing Cabinet, of which the following is a specification.

Our invention relates to a cabinet for the filing of maps and like articles and of different size, and among the objects of the invention may be named; first, to provide a rapid and convenient system of filing maps; second, to facilitate the inspection of the maps and their removal from the cabinet; third, to economize space; and fourth, to provide for an adequate system of indexing.

With the above and other objects in view our invention consists of the parts and the constructions, arrangements and combinations of parts which we will hereinafter describe and claim.

In the accompanying drawings forming part of this specification and in which like reference numerals indicate corresponding parts in the several views;

Figure 1 is a perspective view of a map filing cabinet embodying our invention. Fig. 2 is an enlarged detail showing in section the upper ends of two opposite sides of the cabinet with a suspending rod extending therebetween. Fig. 3 is a cross section of the front of the case showing a portion of one end and the link connection between said front and end. Fig. 4 is an enlarged cross section of one end of the case showing one end of the suspending rod and connections. Fig. 5 is an edge view of one of the suspending hooks. Fig. 6 is a side elevation of the same showing one of the members of the hook moved outwardly in dotted position. Fig. 7 is a bottom plan view of the hook and a portion of the suspending rod.

In carrying out our invention we construct a filing case or cabinet of suitable design or proportion and as herein shown said case includes two similar ends, *a* *a'*, a front, *b*, hinged thereto at its lower edge and a top, *c*, hinged to the back of the case, said top being provided with jointed links which connect it with the ends of the case and hold the top in its open position as indicated in Fig. 1.

The front, *b*, of the case is also provided with pivoted slotted links, *d*, which are ap-

propriately guided in grooves or channels formed by plates or like parts secured to and placed over the upper portion of the ends of the case, as shown. The case may be of any desired dimensions and its construction may vary within reasonable limits without departing from the salient features of the invention. Extending across the case from end to end is a rod, *f*, having perforations, *g*, at suitable points in its length, these perforations being perpendicular to the axis of the rod and being designed to receive the suspending hooks shown in Figs. 5, 6 and 7. One of these hooks is attached to the rod at each of the aforesaid perforations and said hook is preferably formed of two pieces of stiff wire hinged together at *h* to form the two sides, *i*, *i'*, the latter of which is designed to be moved toward and from the companion member to open up the lower portion of the hook to permit the insertion of a map or like article, said hook having both of its members, *i* *i'*, bent at the bottom to form overlapping portions, *j*, *j'*, each of which is provided with notches and said portions adapted, when pressed together, to snap into interlocking contact. In practice, one end of the hook is attached to one of the perforations in the rod so that the hinged joint lies close to the rod, and when the hook is opened and the map inserted, the parts of the hook may be forced past each other so that they will snap into engagement by reason of the elasticity of the wire, of which the hook is formed, thereby retaining the map in position on the hook.

Each end of the rod, *f*, is threaded and fitted to a knob or nut, *l*, which seats upon a shoulder at the upper end of the sides of the case, as shown in Figs. 1, 2 and 4, said knob or nut being of any desired form and being screwed on the end of the rod until it is flush with the end thereof.

In practice, and assuming that the rod with its perforations has been placed in position in the case, the hooks are opened and the longer ends, *i*, are passed through holes with which the map to be suspended is provided, after which the hook is closed and locked as before described. One case such as herein shown and described will accommodate forty or fifty or any other desired number of maps the same length as that of the case or twice the number of maps if they have only one-half the length of said case.

Each rod with the map or maps suspended from it is supported at its ends on the edges of the metal strips, *e*, which are secured on cleats in the ends, *a*, *a'*, of the cabinet, the 5 edges of the metal strips projecting above the cleats so that the nuts, *l*, on the ends of the rod will not touch the cleats when the device rests upon and slides along the metal strips. In this way, the nuts, prevent the 10 device from falling from its position on the metal strips. Filing cabinets may be constructed to accommodate as many of these suspending devices as may be desired. The maps hang close together and thereby avoid 15 any waste space in the cabinet and also any possibility of wrinkling or tearing the maps or other suspended articles.

Since the upper corners of the maps may be placed evenly, it is quite apparent that 20 the maps are readily indexed. When it is desired to inspect any map and remove it from the cabinet, the particular rod and suspended maps are lifted out of the cabinet and laid on a table. Maps on top of the 25 desired one are revolved on the hooks while closed, and the desired map may be inspected or removed by unsnapping the hooks. After replacing the maps and snapping the 30 hooks shut, all maps on the rod fall easily into place and the rod with its suspended maps may be replaced in the cabinet.

Having thus described our invention what we claim as new and desire to secure by Letters Patent is:—

1. A map filing device including rods 35 supported at their ends provided with collars at the ends to prevent longitudinal displacement and perforated at intervals of their lengths, rectangular hangers having one end adapted to pass through the holes 40 in the rods, and the opposite map-supporting link ends separable to allow the maps to be removed or replaced, said ends overlapping and interlocking.

2. In a map filing device, rods having 45 enlarged collars upon the ends, said rods having holes made through them, and hangers consisting of jointed, substantially rectangular links having one end suspended in the holes in the rods and the other ends 50 separable to receive the maps and adapted to overlap and interlock, the lower member of one link being longer than the opposing member to receive a plurality of maps, and said opposing members having interlocking 55 notches closable to retain the maps in place.
